UNITED STATES PATENT OFFICE.

GEORGE E. WEBB, OF MILWAUKEE, WISCONSIN, ASSIGNOR TO KOEHRING COMPANY, OF MILWAUKEE, WISCONSIN, A CORPORATION.

CONCRETE-PAVEMENT-FINISHING MACHINE.

Application filed June 15, 1921. Serial No. 477,779.

To all whom it may concern:

Be it known that I, GEORGE E. WEBB, a citizen of the United States, residing at Milwaukee, in the county of Milwaukee and State of Wisconsin, have invented certain new and useful Improvements in Concrete-Pavement-Finishing Machines, of which the following is a specification.

The art of building concrete roads, pavements, and the like, has progressed today to the extent that the paving can be laid in relatively large areas daily by up-to-date machinery employed, the machinery progressing as the work proceeds and operating over the subgrade on which the pavement is being constructed.

It is the object of the present invention to provide a machine for finishing the pavement, which machine is adapted to travel over the concrete aggregates after they have been laid by a suitable paving machine, strike off the said aggregates to the proper level or contour for the finished road, subject the said aggregates to pressure through the medium of a tamping apron constituting a surface contacting pressure distributing member, and additionally subjecting the surface portion of the aggregates in contact with the said tamping apron, to vertical vibration imparted thereto by a suitable vibrating machine coacting with the said apron. Finally, the machine is designed to apply a final finished and sealed surface to the pavement by means of a brush of suitable substance, all with a view to providing a pavement construction possessing the highest qualities of resistance to the customary wear and tear of traffic thereover, one more dense and strong than now in use.

An essential object of the invention comprising the machine generally set forth above has been to provide mechanical instrumentalities for performing practically all of the work of the machine, and under the control of a single operator. That is to say the machine is motor driven so as to travel upon the road rails or forms between which the aggregates constituting the pavement are laid, its strike off board or blade is mechanically actuated, the tamping apron is carried in proper position for contact with the road surface and extending entirely across said surface, the vibrator which applies pressure, by its weights as well as vibration, to the tamping apron operates auto-

matically, traversing the surface of the said apron by passing back and forth over the latter, and the final finishing means of the machine are likewise mechanically actuated.

I have designed the machine so that the tamping apron may be elevated and thus placed in an inoperative position, facilitating movement of the machine when said apron is not being used for effective operation upon the road surface.

Additionally, my invention comprehends certain features such as a special type of vibrator for the tamping apron, or surface contacting member, special control mechanisms for the carriage upon which the vibrator is mounted and for the driving means of said carriage, together with general control mechanisms for the movement of the machine as a whole when it is advanced to a new position for effective operation of the tamping apron or member.

Other detailed features are comprised within the invention, including a special form of flexible tamping apron, gearing arrangements, and the like, all of which will be more fully understood upon reference to the following description, taken in connection with the annexed drawings, in which:

Figure 1 illustrates a rear elevation of a concrete pavement finishing machine embodying the essential features of my invention.

Figure 2 is a top plan view of the machine, certain parts, including the tamping apron, being broken away to render clear details of construction.

Figure 3 is an end elevation of the machine illustrating the mechanism at the power plant end particularly.

Figure 4 is a plan view, partly in section, of the vibrator carriage, bringing out more clearly the gearing arrangements thereon.

Figure 5 is an end view, partly in section, of the instrumentalities illustrated in Figure 4.

Figure 6 is an end view, partly in section, showing operating means for temporarily elevating the tamping apron, including the operating hand wheel.

Figure 7 is a rear elevation showing more clearly the means shown in Figure 6 and supporting connections for the tamping apron.

Figure 8 is a fragmentary sectional view of a modified form of toothed wheels and

track for obtaining a positive drive mechanism for the vibrator carriage.

Figure 9 is an end view of the parts shown in Figure 8, the track, however, being shown in section.

Figure 10 is a detail view of the main reversing clutch devices.

I have illustrated my invention in connection with the road bed of a typical concrete road, the subgrade of which is designated A, on which subgrade A will be seen the concrete aggregates B, laid in the customary manner between road forms or rails C, which are always provided these days at the opposite sides of a road in process of construction. My machine, as above premised, is adapted to travel upon the forms C and comprises a main support or frame 1 made up of angle irons and channels suitably fabricated together and braced longitudinally by the trusses 2 made up of longitudinals united with vertical and diagonal struts 3.

At its opposite ends the support or frame 1 is mounted upon wheels 4, preferably, though not necessarily, four in number, which wheels operate on the rails C. At one end of the support 1 will be provided a suitable power plant comprising the motor 5, geared, as shown in Figure 3, to operate a main drive shaft 6 which is disposed parallel with one end of the machine. By means of a suitable controlling lever 7 operating a conventional type of clutch mechanism, motor 5 may be connected to drive shaft 6, the motion of which is communicable to an adjacent one or more of the wheels 4 by means of gearing comprising the bevel pinion 8 and bevel gear 9, see Figure 3. Under these conditions it will be evident that an operator adjacent to the motor 5 may readily cause movement of my machine bodily and advance it to a new position over the aggregates on the road bed for suitable finishing operations respecting the latter. At the front end of the machine are located scrapers 10 for scraping the forms or rails C, and at this point also is located the strike off 11 which consists of a long shoe extending the whole length of the machine, operating transverse to the road subgrade, and actuated back and forth longitudinally by means of a pitman 12 operatively connected with the said shaft 6.

In rear of the strike off 11 above described is located a roller 13 which has a peripheral contour corresponding with that which is to be imparted to the surface of the road, in this instance the road roller being of greater diameter at the ends than at the middle. The said roller 13 assists in giving the proper general contour to the road as the machine travels thereover, and after the strike off 11 has preliminarily struck off the aggregates as the initial operation of finish-

ing the surface. To drive the roller 13 I utilize gears 14 and 15, the former operable by the lever 16 to be disconnected from the gear 15 and thus discontinue the rotation of said roller 13.

At the rear of the machine I provide final finishing means comprising a long brush of wire, rattan or the like, designated 17, the same extending the whole length of the machine which corresponds in length to at least the width of the road. The brush 17 is operated like the strike off 11, except that it has a little longer stroke in respect to its longitudinal movement, a pitman 18 being the supporting and actuating means for the brush and being operated from the shaft 6.

Between the roller 13 and the brush 17 I have provided the primary and essential finishing mechanism of my invention. The purpose of this mechanism as outlined hereinbefore is to operate upon the surface of the aggregates placed on the road subgrade so as to subject the surface portions of said aggregates to a certain depth to pressure, and vibration while under such a pressure. This operation creates a relatively dense surface section for the road bed, forcing the larger aggregates well into the body of concrete and into intimate contact with one another. Furthermore, air is driven out of the aggregates and any voids which might otherwise remain are removed, together with excess water if any develops in the operation. The means by which I produce the finishing operation promoting the density of the surface will now be set forth.

It will be observed on reference to Figures 1 and 2 especially that there extends across my machine for its entire length a cable 19 which passes around grooved cable wheels 20 and 21 on the ends of the wheeled support 1, the wheel 20 being carried by a driving shaft 22 located some distance above the shaft 6, and the wheel 21 mounted upon a suitable shaft 23 at the opposite end of the machine. A vertical shaft 24 geared at its lower end to the shaft 6 and having a worm gear at its upper end co-operating with the worm 25 on the shaft 22, see Figure 3, enables motion of the shaft 22 to be transmitted to the shaft 6. Figure 10 shows the clutches *a* and *b* operable by the lever 7 to drive the shaft 22 in either direction. By the operation of a lever 7 the wheel 20 may be driven in either of opposite directions, thereby imparting a corresponding movement to its cable 19. The cable 19 is utilized as an actuating means for moving and vibrating the carriage back and forth longitudinally upon the wheeled support 1, thereby to enable the vibrating means upon said carriage to operate over the entire surface and down upon what I have termed the tamping apron or member 29. The lever

turning the segment 36 the various levers 31 will be operated until the apron 29 is lowered and rests upon the concrete aggregates. The machine will have been previously moved along the road rails C to strike off the aggregates by use of the strike off shoe 11, and roll them to the general contour of the road about to be constructed, through the action of the roller 13.

The machine being located above the section of the road to be finished, and the apron 29 having been adjusted to its lowermost position in contact with the surface aggregates, the next thing done is to operate the lever 26 and the clutch member 27 to cause operation of the actuating wheel 20 and the operating cable 19. When the cable 19 begins to operate its motion is imparted to the carriage through the means previously described, including the wheels 43 and 44 and gearing, and the weights 58 begin to operate to impart vertical vibration to the carriage and the rollers 59. This vibration is necessarily transmitted to the apron 29 and the effect is an intermittent pounding or tamping operation, incident to the pounding of the rollers 59 upon and in contact with the tamping apron 29.

As the concrete aggregates when struck off are relatively loose and not down to the finished grade, the wheels 41 of the carriage will not be in operating contact with the rails 42, but a slippage of the wheels on the rails will take place. Gradually, however, the vibrator mechanism which I have described, through its action upon the apron 29, will compact the concrete aggregates, rendering the same more and more dense as the machine operates and gradually bringing them down, so to speak, to the final or finished grade for the road surface. Necessarily, when the carriage which starts its operation at either end of the machine, corresponding with either side of the road bed, has tamped, compacted, or densified, the surface aggregates to the extent desired and required, and as limited by the degree of down movement of the rollers 41 until they contact with the rails 42, the efficiency of the carriage and its vibrator mechanism upon that part section of the road aggregates treated, ends. Under these conditions as the rollers 41 are constantly rotated, when they have sufficient frictional engagement with the tracks 42 to produce traction capable of advancing the carriage, the latter moves along the main support 1, and along the tracks 42 of course, to a new position, over the apron 29, and the loose aggregates beneath the latter. The vibrator mechanism is in continuous operation, of course, and the action of compacting, pounding, and tamping the new section of the road bed, beneath the carriage and rollers 59, goes forward. In effect the carriage 40 will gradually move along the machine,

and transversely of the road bed, until the whole width of the section of the bed beneath the apron 29 has been operated upon and rendered of the required density desired to be produced. When the carriage reaches an end of the machine in its progressive tamping action upon the apron 29 the operator will reverse its operation through shifting of the lever 27 and controlling clutch mechanism.

After the particular section of the road bed over which the machine is disposed has been tamped to the desired extent by the operation of the mechanism just set forth, the proper use or manipulation of the levers 7 and 26 will cause the machine as a whole to advance until it assumes a position over a fresh untamped section of the laid aggregates, and the tamping and compacting operation is renewed and carried out in the manner fully explained above.

Should it not be desired to rely upon the automatic action of the carriage, through the co-operation of the rollers 41 with the rails 42 incident to the traction intermediate these parts, I propose a positive drive means for the carriage, which is illustrated in Figures 8 and 9. The said means includes modifying the form of the rollers 41 by toothing these rollers so that they have the form shown in Figures 8 and 9 where they are designated 41^a. The teeth of the rollers 41^a in this construction will engage with the links of a sprocket chain 60 which will be laid upon and fastened to the rails 42 in any suitable manner. By utilizing the parts 41^a and 60 it is evident that a positive feed for the carriage 40 is obtained, and under certain conditions such feed may be found highly desirable. When I use the positive feed means just set forth I prefer to employ automatic instrumentalities for reversing the clutch lever 7 and thereby reversing the direction of movement of the carriage 40 when it reaches an end of the machine. With the foregoing in view I show in Figure 2 clutch reversing devices which include trip levers 61 and 62 are connected to be shifted simultaneously by means of an endless cable 63 which is itself connected to pass about a pulley wheel 64 adjacent to the lever 16 and the lever 26 and upon a shaft 65. The shaft 65 has an arm 66 connected by a link or any suitable device 67 with the lever 7. The lever 7 will be shifted in one direction to cause movement of the carriage 40 in a suitably reversed direction, when the carriage 40 approaches and trips the lever 61 by abutment therewith, and in like manner when the carriage 40 approaches the end of the machine having the motor 5 thereon said carriage is adapted to trip the lever 62 and accomplish opposite movement of the carriage. By manual adjustment of the lever 7 to an intermediate position, the operation of the

130

26 by moving the member 27, causes driving of either the wheel 20, or worm 25.

The tamping member is best seen in Figures 1, 2, and 7, and comprises a flexible concrete surface contacting member made up of a series of boards or slats arranged longitudinally of the road bed and fastened in a substantial manner to the cross pieces 30, which extend transversely, of the road bed. 10 The apron 29 is flexible so that it may readily conform to the struck off contour of the road surface. As shown in Figure 7 the slats or boards of the apron 29 are slightly spaced apart and the apron is carried by a series of angle levers 31 fixed to shafts 32. Rods 33 descend from the lower arms of the levers 31, resiliently connect the apron with said arms through the employment of the springs 34, and generally form a suitable 15 suspension means for the apron, connecting it to the shafts 32 aforesaid. The upper arms of the levers 31, or certain of them, are connected by an actuating rod 35. On one of the shafts 32, that nearest to the 20 motor plant end of the machine, is a toothed sector 36 which is engaged by a worm 37 adapted to be turned by a shaft 38 carrying the hand wheel 39. By operation of the hand wheel 39 it is evident that the apron 29 may be temporarily raised so as to be 25 elevated above the surface of the road aggregates, to be placed out of use, or to facilitate movement of the machine from one place to another. 30 In the operation of finishing the road surface the apron 29 will be lowered so as to rest in contact with said surface, and the vibrating means now to be described is set in operation to apply pressure, and vibration to the said apron 29, to accomplish the results which have heretofore been presented. 35

My vibrating means comprises a carriage shown in Figures 1 and 2 in conjunction with the general machine, and by itself in Figures 4 and 5. This carriage is designed to traverse the machine by moving back and forth along the main wheeled support 1, the weight of the carriage and its parts bearing upon the apron 29, the vibrating means being supported by the carriage to impart vibration thereto, and to pressure rollers thereon, which pressure rollers are in direct engagement with the apron 29. As seen in Figures 1 and 2 the carriage, designated 40, is equipped with four flanged wheels or rollers 41, adapted to operate upon a track 42 carried by the main support 1. The carriage 40 is propelled by the driving cable 19 previously described, said cable passing around suitable grooved wheels 43 and 44, mounted upon shafts 45, suitably journaled upon the frame of the carriage. The lower bight of the cable 19 passes about the carriage operating wheels 43 and 44 aforesaid, the motion

of the wheels being transmitted through the shafts 45 to the wheels 41 by the use of special gearing. This gearing may comprise the horizontal shaft 46 having bevel pinions 47 engaging corresponding pinions 48 upon axles 49 to which the rollers 41 are affixed. The shaft 46, one of which is illustrated fully in Figure 5, may be driven by means such as a worm 50 operated by a worm gear 51 upon a central shaft 52. The shaft 52 is 75 driven in any suitable manner from the shafts 45 through sprocket gear and chain connections generally designated at 53. Mounted upon the carriage 40 in suitable gear housings are drive gears 54 supported by the shaft 52 and engaging driven gear 55, which is carried by a shaft 55^a driving a weighted gear 56 operating in mesh with a corresponding weighted gear 57. The weights on the gears 56 and 57 are designated at 58 and it will be observed that two of the gear housings are utilized, one at each side of the carriage, and the arrangement of the gears just described is duplicated, practically speaking, in these two 80 housings. 85

The weights 58 on the weighted gears above mentioned are so disposed that when the gears are operated from the shafts 45, the rotation of the weights 58 generates forces which are substantially balanced in a horizontal direction but unbalanced in a vertical direction, the unbalanced forces operating in alternation vertically in an evident manner. I utilize the action of the weights 58 under rotation to produce vertical vibrations of the carriage 40 and all of its connected parts, substantially speaking. At the lower portion of the carriage 40 are mounted rollers 59 which operate upon the apron 29 by contact therewith, the weight of the carriage being adapted to be received on the apron 29 during the finishing operation upon the road aggregates, and until the action of the pressure and vibration of the carriage and its rollers 59 has produced the desired dense surface intended to be produced by the action of the machine. The down movement of the carriage and rollers 59 and pressure thereof on the apron 29 is limited by the co-operation of the rollers 41 with the rails 42, as will be more fully pointed out in the general description of the operation of the invention now to be set forth. 100

110 It will be supposed that the machine of this invention is about to be put into operation. A certain section of the concrete of the road or pavement has been deposited upon the sub-grade by emplacing the aggregates in the usual way, as by a paver or any machine such as generally used. Assuming that the apron 29 has been raised and that the machine hereof has been temporarily out of use, the first thing done by an operator is to actuate the hand wheel 39 and by 115 120 125 130

carriage may be entirely discontinued, through the discontinuance of the drive of the actuating wheel 20.

While I preferably only use the clutch reversing mechanism just set forth when the positive feed means for the carriage is employed, it will be understood that I can utilize said reversing mechanism with the type of construction or carriage driving means as 10 first set forth herein.

It is notable that to maintain the cable 19 taut I preferably support the shaft 23 carrying the wheel 21, about which the cable 19 passes, upon pivoted brackets 23^a upon 15 which a normal pull in an outward direction is maintained through the provision of springs 23^b. Any suitable cable tensioning device, many of which are conventional in the various arts, may be employed.

20 It will be evident that the operating shaft 38 might well be actuated from the motor 5 if so desired.

By way of re-capitulation it may be observed that when the lever 7 is in its neutral position, see Figure 10, the driving of the engine to operate the shaft 22 is discontinued and the machine will be at a standstill; likewise, the drive from the engine to the cable operating wheel 20 is inactive. Adjustment of the lever 7 to bring into action one of the reversing clutches 7^a and 7^b, see Figure 10, causes rotation of the shaft 22, and by adjustment of the lever 26 the driving of the wheel 20 may be obtained through connection with the clutch members 27 and 28. The reversing of this drive action on the wheel 20 is of course obtained through the shifting of the lever 7 in reverse directions.

40 The shifting of the lever 26 to connect the clutch members 27 and 29 is effective to transmit the drive from the engine to the shaft 6, when it is desired to advance the machine bodily upon the supporting rails 45 C, the motion of the shaft 22 being transmitted to the shaft 6, under these conditions through the worm 25, shaft 24, and bevel gearing intermediate the shafts 26 and 24. Obviously, members 11, 17, and 13 are 50 operable only when the clutch devices 27 and 29 are effective.

It is of importance to have four wheels for the positive driving of the vibrator in its progress over the flexible apron on account of the flexible nature of the latter. This factor renders it possible for the forward wheels of the carriage of the vibrator to at times become disengaged from the sprocket chains with which they are cooperative. In such event, the rear wheels must do the driving. When the aggregates have been tamped to the proper road grade or contour the driving wheels are fully engaged with the driving chains on the tracks. 60 Under the conditions stated, therefore, at

no time is the positive driving of the carriage discontinued, something essential in the operation of the machine.

The fabricated frame work of the main portable support for the machine may be 70 comprised of sections or parts susceptible of adjustable connection so as to vary the operating length of the machine to conform with roads of different widths.

By the use of the present machine it will 75 be clear that a very superior road surface is produced, especially on account of the fact that the upper layers of the aggregates are caused to be arranged so as to resist wear to the highest degree possible owing to the 80 fact that their flat sides are uppermost.

The carriage and vibrating means thereon may broadly be considered a vibrator, for they function as such, and also viewed 85 generally as a tamper.

Note may be made of the fact that my invention resides not only in my general machine, as a whole, but in certain unit features thereof which are susceptible of individual employment or have functions useful independently of their combination with all other parts of the machine.

Having thus described my invention what I claim as new is:

1. In a concrete finishing machine, the combination of a portable support a tamping apron thereon adapted to contact with the concrete surface to be finished, a vibrator thereon operating in engagement with said apron, means to move the vibrator along the apron and means for actuating the vibrator to press on and vibrate the apron.

2. In a concrete finishing machine, the combination of a support adapted to travel over freshly laid concrete aggregates, tamping mechanism carried by the support for operating on said concrete aggregates, means normally supporting the tamping mechanism to travel over the aggregates operated upon and means engageable with the tamping mechanism after it has lowered through tamping action upon the aggregates to effect movement of the tamping mechanism to a new position relatively to the aggregates operated upon.

3. In a concrete finishing machine, the combination of a tamping apron adapted to contact with the concrete surface to be finished, a vibrator operating in engagement with said apron, a means for moving the vibrator over the apron, and common propelling means for the vibrator and the machine as a whole.

4. In a concrete finishing machine, the combination of a tamping apron adapted to contact with the concrete surface to be finished, a vibrator operating in engagement with said apron, a means for moving the vibrator for effective action upon

the upper surface of the apron, and common means to propel the machine, actuate the vibrator upon the machine, and effect vibratory action of the vibrator.

5. In a concrete finishing machine, the combination of a tamping apron adapted to contact with the concrete surface to be finished, a vibrator operating in engagement with said apron, a means for moving the 10 vibrator over the apron, the machine being adapted to span a road bed, supporting means for the vibrator to cause movement thereof transverse to the road bed, and means to constantly actuate said supporting 15 means.

6. In a concrete finishing machine, the combination of a mobile support adapted to operate above a road bed, and tamping means including a mobile vibrator movable 20 bodily on said support independently of its vibrations and means to cause said vibrator to cause pressure on a plastic substance and vibrate the latter while under pressure.

7. In a concrete finishing machine, the 25 combination of a mobile support adapted to operate above a road bed, a tamping means including a mobile vibrator movable bodily on said support independently of its vibrations, and a pressure distributing concrete 30 contacting member carried by the support intermediate the vibrator and road surface operated on.

8. In a concrete finishing machine, the 35 combination of a mobile support adapted to operate above a road bed, a tamping means including a mobile vibrator, a pressure distributing concrete contacting member intermediate the vibrator and road surface operated on, and means to maintain the said 40 member in contact with said road surface, and the vibrator in engagement with said member, and means to actuate the vibrator for a pressure and vibrating effect on the contacting member.

45. 9. In a concrete finishing machine, in combination, a portable support, propelling means therefor, a tamping apron suspended from the support, and a vibrator movably operating to travel along the upper 50 surface of the apron, and vibrative independently of such movement.

10. In a concrete finishing machine, in combination, a portable support, propelling means therefor, a tamping apron suspended 55 from the support, a vibrator movable over the surface of the apron, and vibrative independently of such movement, and a prime mover common to the propelling means and the vibrator, and adapted to operate the 60 latter for both its movement over the apron and for the vibration thereof.

11. In a concrete pavement finishing machine, in combination, a portable support adapted to travel along and over the road 65 bed to be finished, a movable tamper on said

support, a means to propel the tamper upon the support, and means to automatically reverse the movement of the tamper in its travel upon the support.

12. In a concrete finishing machine, in combination, a portable support adapted to span a road bed, a strike-off at the front of the support, a surface roller at the rear of the strike-off, a tamping mechanism in rear of the roller, and a finishing brush at the rear of tamping mechanism, all carried by 75 said support.

13. In a concrete finishing machine, in combination, a portable support adapted to span a road bed, a strike-off at the front of 80 the support, a surface roller at the rear of the strike-off, a tamping mechanism in rear of the roller, a finishing brush at the rear of tamping mechanism, all carried by said support, and means to reciprocate the strike-off and brush upon the support.

14. In a concrete finishing machine, in combination, a portable support adapted to span a road bed, a strike-off at the front of 90 the support, a surface at the rear of the strike-off, a tamping mechanism in rear of the roller, a finishing brush at the rear of tamping mechanism, all carried by said support, and means common to each to operate the strike-off, tamping mechanism, and 95 brush.

15. A machine as claimed in claim 1, combined with means to raise and lower the apron to render it inoperative, and operative, respectively.

16. A machine as claimed in claim 7, together with means operable to raise and lower the apron relatively to the road surface operated upon

105. 17. Concrete finishing mechanism comprising a portable support, tamping devices including a vibrator carried along by the support, means whereby said vibrator may be shifted bodily on the support, and means to effect its vibration, consisting of weight devices co-operating to create forces balanced in a horizontal direction, and unbalanced in a vertical direction, the latter forces acting to cause vibration of the vibrator.

110. 18. Concrete finishing mechanism comprising a portable support, and instrumentalities thereon consisting of tamping devices including a vibrator, means whereby said vibrator may be shifted bodily, and means to effect its vibration, consisting of weight devices co-operating to create forces balanced in a horizontal direction, and unbalanced in a vertical direction, the latter forces acting to cause vibration of the vibrator, and a concrete contacting member over 115 which the vibrator engages and operates.

120. 19. In a concrete finishing machine, in combination, a portable support to travel over a road subgrade containing concrete aggregates, tamping mechanism adapted to 125

travel upon said support and including a carriage having travel wheels and traction supporting means for the carriage cooperative therewith when the travel wheels engage

5 said traction supporting means by lowering movement of the carriage on the concrete aggregates operated upon, to effect movement of the carriage to a new position relatively to the concrete aggregates to act on a fresh

10 portion of the latter.

20. In a concrete finishing machine, a combination of a portable support to travel over a road bed, a concrete contacting apron carried by said support, and tamping means 15 mounted upon the support and shiftable over the upper surface area of the contacting apron during operation of said tamping means, with means for moving the tamping means back and forth while engaged with the

20 contacting apron.

21. In a concrete finishing machine, a combination of a portable support to travel over a road bed, a concrete contacting apron carried by said support, and tamping means 25 mounted upon the support and shiftable over the upper surface area of the contacting apron during operation of said tamping means, with means for moving the tamping means back and forth while engaged with the

30 contacting apron, the last mentioned means comprising a motor on said support, driving means from said motor leading to the tamping means for shifting the same relatively to the contacting member, and for vi-

35 brating said tamping means.

22. In a concrete finishing machine, a combination of a portable support to travel over a road bed, a concrete contacting apron carried by said support, and tamping means 40 mounted upon the support and shiftable over the upper surface area of the contacting apron during operation of said tamping means, with means for moving the tamping means back and forth while engaged with

45 the contacting apron, the last mentioned means comprising a motor on said support, driving means from said motor leading to the tamping means for shifting the same relatively to the contacting member, and for

vibrating said tamping means, together with 50 automatic means for reversing the direction of movement of the tamping means upon the support.

23. In a concrete finishing machine the combination of a portable support adapted 55 to travel over a road bed, a concrete contacting member carried by said support, a carriage movable upon the support transversely to the road bed, a vibrator upon said carriage engaging with the contacting member and exerting a pressure thereupon, cable driving means connected with the carriage for propelling the same and connected with the vibrator for effecting vibration thereof, and a power means for operating 60 said cable means.

24. A machine as claimed in claim 23, combined with instrumentalities for reversing the movement of the carriage upon the support. 70

25. A machine as claimed in claim 23 wherein the contacting member is made up of a series of connected boards or slats closely spaced apart.

26. Means as claimed in claim 23 combined 75 with an elevating device for raising and lowering the contacting member and the carriage.

27. A concrete tamping mechanism comprising the carriage adapted to travel over 80 a road bed, and a vibrating engine mounted upon said carriage, said vibrating engine comprising rotative weight devices so arranged relatively to each other that during rotation they create unbalanced forces 85 operating in vertical direction, and balanced forces operating in a horizontal direction, thereby communicating alternating vertical vibrations to the carriage, and pressure means upon the carriage adapted to act 90 with tamping effect upon the road bed through vibrative action of said weight means.

28. A machine as claimed in claim 26 combined with propelling means for the carriage and the vibrating weight devices. 95

In testimony whereof I affix my signature.

GEORGE E. WEBB.
